UNITED STATES PATENT OFFICE.

WM. E. MEGINNIS, OF PHILADELPHIA, PENNSYLVANIA.

LADY'S CORDED SKIRT.

Specification of Letters Patent No. 5,441, dated February 8, 1848.

To all whom it may concern:

Be it known that I, WILLIAM E. MEGINNIS, of the city and county of Philadelphia and State of Pennsylvania, have invented a new and useful Improvement in the Method of Making Ladies' Self-Adjusting Skirts, which is described as follows, reference being had to the annexed drawings of the same, making part of this specification.

10 Figure 1, represents a specimen of skirt-
ing, made with twisted manila thread, in
which the fibers of the alternate threads or
cords are twisted in contrary directions to
prevent kinking. Fig. 2, is a specimen of
15 thread composed of two strands differently
twisted—that is to say—the fibers of one
being twisted to the right and the other to
the left, laid together and wrapped. Fig.
3, is a specimen of thread or cord, in which
20 right and left twisted strands are themselves
twisted together, and wrapped with silk or
other thread. Fig. 4, is a specimen of
thread or cord, in which the fibers are laid
in straight parallel lines, and wrapped.

25 My improvement is designed to remove
the objections to the use of the fabric manu-
factured and patented by D. Hough, in
June, 1846, arising principally from its
kinking and deranging the dress of the
30 wearer—and to the fabric patented by S.
Folsom in December, 1846—which is liable
to the same objection.

The sissal or manila hemp in the Hough
fabric, is twisted in one direction to form
35 the thread or cord, and not wrapped with
any material to hold the fibers or strands
together, depending altogether upon its
twist, and being interwoven with the cotton,
or other material of which the skirting is
40 made, in horizontal parallel lines to give it
elasticity, will, when made into a skirt, form
a series of horizontal circles, each circle
having a tendency to kink in the direction
of the twist horizontally. The Folsom
45 fabric, which is composed of thread twisted
in the same manner, but arranged differently
being in zig-zag, serpentine, and other lines
will have a tendency to, and in fact will,
kink vertically, obliquely, and horizontally,
50 and extend the dress upward, when the
wearer is seated, giving it the appearance of
a number of inflated bags.

55 My improvement consists in twisting
strands of manila, hair, or other elastic sub-
stance, used to form the thread, in contrary
directions, and wrapping the same with a

thread of cotton, silk, or other suitable ma-
terial, to bind the fibers of manila, or hair,
together, as represented at A, B, Fig. 1,—
and then weaving the manila, or hair
strands, or thread into the cotton, linen, or
other article of which the skirt is made, in
parallel lines, in alternate order—that is to
say, first a thread A twisted to the right,—
then parallel to this at the required distance
60 apart, a thread B, that has been twisted to
the left,—then another twisted to the right,
and so on, as shown in Fig. 1. This fabric
being formed into a skirt, will not be liable
65 to kink, because the tendency to kink in one
direction caused by the right twist A, in
one of the circles of thread or cord will be
counteracted by the exertion to kink in the
opposite direction by the left twist B in the
70 next parallel circle. The elasticity of the
75 skirt (vertically) is produced by the warp
of the cloth.

I sometimes form the thread in a manner
to do away with its tendency to kink, by
taking a right and left twisted thread and
laying these two together, and wrapping
them in the manner above described. The
twist of one strand will then counteract the
twist in the other in the tendency to
kink, as represented in Fig. 2. This de-
80 scription of thread is woven into the cloth
in parallel lines in the same manner as
above described with Fig. 1. Manila hemp
being short necessarily requires to be twist-
ed, or spun together, and will not retain its
90 twist well without being wrapped with a
thread, or confined by other similar means.
I likewise take a right and left twisted
thread and twist these two together, which
will produce an equilibrium of twist by
95 itself and thus prevent kinking—the effort
of one thread to kink is one direction being
counteracted or balanced by the effort of the
other thread to kink in an opposite direc-
tion as shown in Fig. 3. The two threads
100 thus twisted, may be wrapped (or left un-
wrapped) as preferred.

I sometimes make the skirting of thread
composed of fibers laid parallel, and
wrapped, as shown in Fig. 4. Skirting
105 made in the manner above described of
thread, twisted in opposite directions and
interwoven with the cloth, is far superior to
any other ever made, and will retain its de-
sired position, and when pressed upon, will
110 as soon as the pressure is removed resume
its former position, and when deranged by

the wearer sitting down will return to its required position on rising and when wet, or washed, will not lose its elasticity and proper shape.

5 I do not claim to be the original inventor of interweaving manila, hair, or other elastic material into, or combining with the cloth of which skirting is composed, but

10 What I do claim as my invention, and desire to secure by Letters Patent in the before described method of making "ladies' self adjusting skirts," is—

15 66 Interweaving in alternate order threads or cords of manila or other elastic material, twisted in opposite directions, with the cloth of which the skirt is composed, in al-

ternate order, so that a thread or cord, whose fibers are twisted to the left shall counteract the tendency to kink of the next adjacent cord or thread whose fibers are 20 twisted to the right by which the skirting is prevented from kinking, and by which the dress is retained in a proper position, whether the cords be composed of one or more strands arranged in the manner above 25 described, or made in any other mode which is substantially the same, by which analogous results are produced.

WILLIAM E. MEGINNIS.
